(57) **CLAIM**

The ornamental design for a roof rack watercraft attachment as shown and described.

DESCRIPTION

FIG. 1 is a front perspective view of the roof rack watercraft attachment showing my new design;

FIG. 2 is a front plan view thereof;

FIG. 3 is a rear plan view thereof;

FIG. 4 is a side elevation view thereof;

FIG. 5 is the other side elevation view thereof;

FIG. 6 is a top plan view thereof;

FIG. 7 is a bottom plan view thereof;

FIG. 8 is a front perspective view with the roof rack rod attachment in a loading position;

FIG. 9 is a front plan view of FIG. 8;

FIG. 10 is a side elevation view of FIG. 8;

FIG. 11 is a top plan view of FIG. 8;

FIG. 12 is a bottom plan view of FIG. 8; and,

FIG. 13 is an environmental perspective view of FIG. 8.

The broken lines in the drawings illustrate portions of the environment that form no part of the claimed design.
